AUTOMATIC VALVE MECHANISM

Charles M. Terry, Decatur, Ill., assignor to A. W. Cash Company, Decatur, Ill., a corporation of Delaware

Application June 17, 1943, Serial No. 491,100

8 Claims. (Cl. 137—153)

This invention relates to automatic valve mechanisms, and more particularly to the construction and arrangement of a valve which will operate to maintain a substantially constant drop in the pressure of the fluid traveling therethrough.

In certain installations of oil cooling equipment there is need for an automatic valve for use in a by-pass line. The viscosity of oil varies greatly with its temperature, and if an oil cooler is designed for a normal pressure drop of say eleven pounds, it will be found that when starting up with the oil cold the pressure drop may run as high as forty or fifty pounds. This high pressure drop may be avoided by allowing a considerable portion of the oil to by-pass the cooler through a suitable valve, which should preferably open automatically to the required extent.

It is accordingly one object of the invention to provide an automatic valve mechanism of simple, inexpensive and dependable construction which will restrict the flow of fluid in such a manner as to maintain a substantially constant drop in the fluid pressure.

It is a further object of the invention to provide an automatic valve mechanism arranged to respond to variations in a fluid pressure differential and so constructed as to operate steadily without surging or fluttering.

It is a further object of the invention to provide an automatic valve mechanism arranged to respond to changes in the pressure drop across the valve and so constructed that a slight increase in the said pressure drop will cause the valve to open to a comparatively large extent.

It is a further object of the invention to provide an automatic valve mechanism arranged to maintain a substantially constant drop in the fluid pressure and capable of handling fluid at a rate of flow which is very high in proportion to the size of the mechanism.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts:

Fig. 1 is a longitudinal section through an automatic valve mechanism;

Fig. 2 is an elevation of a valve member forming a part of the mechanism;

Fig. 3 is a fragmentary sectional view showing a slightly modified construction; and

Fig. 4 is a fragmentary sectional view showing a further modification.

The embodiment illustrated comprises a hollow body or casing 10, preferably of integral construction, which is divided internally by a partition 11 to provide an inlet chamber 12 and an outlet chamber 14. The body 10 is provided on opposite sides with external openings 15 and 16 which communicate with the inlet and outlet chambers respectively, these openings being surrounded by flanges 17 so that the body may be readily connected to inlet and outlet pipes (not shown). The partition 11 is shaped as a horizontally positioned U, with the interior of the U forming a portion of the outlet chamber 14. Each of the two horizontal branches of the U is provided with a cylindrical port 18, the two ports being vertically aligned and of the same diameter. Within these ports there is mounted a vertically slideable valve member 19 of the balanced type having two cylindrical portions or disks 20 to control the flow through the ports, these disks being connected by a vertical stem 21. Guide wings 22 depend from each disk 20 to engage the walls of the ports and maintain the valve member in proper alignment with the ports. Upward movement of the valve member opens the ports for increased flow of fluid therethrough.

Means is provided to steady the movements of this valve member and prevent surging or fluttering thereof. For this purpose the body 10 is shaped to provide a vertical cylindrical bore 24 directly beneath the lower port 18 and aligned therewith. A plate 25 is secured to the bottom 30 of the body to close the lower end of this bore. Within the bore 24 there is mounted a vertically slideable piston 26 which is connected to the lower disk 20 of the valve member by means of a vertical stem 28. A restricted port 29 extends through the piston 26 to form a by-pass. This construction provides a dashpot whereby the desired steadyng effect is obtained.

In order to control the operation of the valve in accordance with the fluid pressure drop across the same, the body 10 is shaped to provide an opening in the form of a vertical cylindrical bore 31 directly above the upper port 18 and aligned therewith. This bore preferably has substantially the same diameter as the port. The upper end of the bore 31 communicates with the interior of a chamber 32 which is secured to the top of the body. A piston 33, forming a fluid-pressure responsive device, is vertically slideable in the bore 31, and in the embodiment shown in Fig. 1 this piston is integral with the valve member 19. The

piston 33 and valve member 19 are urged downwardly by means of a vertical coiled compression spring 35 which extends upwardly into the chamber 32. The upper end of the spring engages a button 36 on the lower end of a vertical screw 37 which is threaded through the top of the chamber 32. A cap 38 is mounted on the upper portion of the screw to engage the top of the spring chamber and prevent any leakage of fluid. The interior of the spring chamber is connected with the outlet chamber 14, and for this purpose a passage 40 extends downwardly through the center of the upper disk 20 and the stem 21 to intersect with a passage 41 which extends diametrically through the stem 21.

It will now be apparent that the valve member 19 is urged upwardly toward its open position by the pressure of the fluid in the inlet chamber 12, this pressure being effective beneath the dashpot piston 26 and the lower valve disk 20. This upward force is opposed by the downward force of the spring 35 and by the fluid pressure inside the chamber 32, this pressure being effective above the piston 33 and being equal (under static conditions) to the pressure in the outlet chamber. Thus the valve will remain closed so long as the fluid pressure differential between the inlet chamber and the outlet chamber is below a predetermined value which is dependent upon the adjustment of the screw 37. Whenever the pressure differential exceeds the said predetermined value, the valve member will be raised to allow flow through the ports 18.

Preferably the construction is such that a comparatively slight increase in the pressure differential will open the valve widely and thus allow a large volume of fluid to flow through the valve. This is accomplished by utilizing the flow of the fluid to cause a reduction in the pressure above the piston 33 as compared with the pressure in the outlet chamber 14. For this purpose I prefer to utilize the fluid flowing through the upper port 18 to create an aspirating effect on the passage 41. As indicated by the small arrows in Fig. 1, the fluid entering the outlet chamber 14 through the upper port 18 tends to travel at comparatively high velocity downwardly along the stem 21. Directly above the passage 41 this stem is provided with a baffle plate in the form of an outwardly extending flange or rib 43 which preferably completely surrounds the valve stem. This baffle serves to direct the downwardly flowing fluid in an outward direction away from the stem, and this has the effect of reducing the pressure beneath the baffle and thereby aspirating fluid out of the chamber 32 through the passages 40 and 41. As a result the pressure above the piston 33 is reduced, causing the valve to open much farther than it would otherwise, and permitting a much greater flow to take place. The lower surface of the baffle 43 forms a downwardly facing shoulder.

Valves of the larger sizes are of course connected to larger pipes, and these pipes are so stiff and heavy that in some cases they may impose appreciable mechanical stresses on the valve body 10 and distort the same slightly. The dashpot piston 26 will ordinarily be made a rather loose fit in its bore 24, and hence will always shift freely. The valve disks 20 and the upper piston 33 should however fit rather closely in their respective bores in order to minimize leakage of fluid and any appreciable distortion of the valve body 10 might cause them to bind. In order to avoid this possibility, the piston 33 in the larger valves

may be made separate from the valve disks 20, as shown in Fig. 3. With this construction the piston merely rests on the upper valve disk and is free to move laterally thereon, so that slight misalignment of the bores will not prevent free sliding of the valve member and pistons.

In Fig. 4 there is shown a further modification showing a slightly different arrangement for obtaining the desired aspirating effect. In this embodiment the valve stem 19 is somewhat reduced in diameter to provide a downwardly facing shoulder 46 beneath the upper valve disk 20 and adjacent to the valve stem. The passage 40-41 of Fig. 1 is replaced in Fig. 4 by one or more substantially vertical passages 47 which extend through the upper disk 20, with their lower ends opening through the shoulder 46. When the valve is open, the fluid traveling downwardly through the upper port 18 will create a zone of relatively low pressure directly beneath the shoulder 46, and fluid will therefore be aspirated out of the chamber 32 through the passages 47. This will cause the valve to open much farther and permit the rate of flow to increase considerably.

The operation of the invention will now be apparent from the above disclosure. The screw 37 will be adjusted so that the valve will start to open at a desired pressure differential of say fifteen pounds. So long as the pressure differential is less than fifteen pounds, the fluid pressure above the piston 33 added to the force of the spring 35 will hold the valve closed against the fluid pressure beneath the lower valve disk 20. If however the pressure differential exceeds fifteen pounds, the fluid pressure beneath the lower valve disk will lift the valve member 19 and flow will take place through the ports 18. In the embodiment shown in Figs. 1 to 3, the fluid passing through the upper port will travel downwardly along the stem 19 until it encounters the baffle 43, which will deflect the fluid outwardly away from the stem and thereby aspirate fluid from the passage 41 beneath the baffle. This will reduce the pressure above the piston 33 to a value appreciably below the pressure in the outlet chamber 14, and cause the valve to open much farther than it would otherwise. As a result flow can take place at a comparatively high rate with only a slight increase in the pressure differential. In order to ascertain the effect of the baffle 43, tests were run on a valve mechanism 1½ inch nominal pipe size both with and without the baffle. In each case the valve was adjusted to start opening at a pressure differential of 14½ pounds per square inch. Without the baffle an increase of 3 pounds in the pressure differential produced a flow of 22 gallons per minute, whereas with the baffle the same increase in the pressure differential produced a flow of 110 gallons per minute. Thus the addition of the baffle increased the capacity of the valve five-fold under these particular conditions, with the pressure differential across the valve 17½ pounds. Without the baffle it was found that the pressure differential had to be increased to 20 pounds to produce a flow of only 42 gallons per minute. The practical advantages of this feature will be apparent to those skilled in the art. The mechanism operates smoothly at all times, the dashpot 26 serving to prevent surging and fluttering. The bores 31, 18 and 24 in the valve body are all aligned and of the same diameter. They can all be machined at one set up, greatly decreasing the cost of

manufacture. The entire mechanism is simple, inexpensive and dependable.

The operation of the embodiment shown in Fig. 4 is similar to that of the Fig. 1 construction. The fluid flowing downwardly from the upper port 18 will create a low pressure zone beneath the shoulder 48 similar to the low pressure zone beneath the baffle 43 of Fig. 1. Thus fluid will be aspirated from the passages 47, and the pressure above the piston 33 will be reduced, causing the valve to open and allow an increased flow of fluid for a given pressure differential.

In the claims, certain terms such as "upper," "lower," "vertical," "horizontal," and the like are employed. It should be noted however that the apparatus can be mounted in positions other than that illustrated, and such terms are not intended as limitations except as they describe the relative positions of the various parts.

Having thus described my invention, what I claim as new and desire to secure by Letters Patent is:

1. Automatic valve mechanism comprising a hollow body, a partition shaped as a horizontally positioned U dividing the interior of the body into an inlet chamber and an outlet chamber, the interior of the U forming a portion of the outlet chamber and each branch of the U having a port therein with the ports vertically aligned, a vertically reciprocable valve member having two vertically spaced disks thereon connected by a central stem, the disks being associated with the respective ports to control the flow therethrough and closing in a downward direction, the body having a vertical bore therein above the upper port, a piston slideable in the bore and connected to the valve member, the valve member having a passage therein which connects the outlet chamber with the space above the piston, means to utilize the fluid flowing through the upper port to aspirate fluid from the passage and thereby reduce the pressure above the piston, and a spring urging the valve member downwardly.

2. Automatic valve mechanism comprising a hollow body, a partition shaped as a horizontally positioned U dividing the interior of the body into an inlet chamber and an outlet chamber, the interior of the U forming a portion of the outlet chamber and each branch of the U having a port therein with the ports vertically aligned, a vertically reciprocable valve member having two vertically spaced disks thereon connected by a central stem, the disks being associated with the respective ports to control the flow therethrough and closing in a downward direction, the body having a vertical bore therein above the upper port, a piston slideable in the bore and connected to the valve member, the valve member being shaped to provide a downwardly facing shoulder adjacent the stem and a passage connecting the space directly beneath the shoulder with the space above the piston, whereby fluid flowing downwardly from the upper port past the shoulder will aspirate fluid from the passage and reduce the pressure above the piston, and a spring urging the valve member downwardly.

3. Automatic valve mechanism comprising a hollow body, a partition shaped as a horizontally positioned U dividing the interior of the body into an inlet chamber and an outlet chamber, the interior of the U forming a portion of the outlet chamber and each branch of the U having a port therein with the ports vertically aligned, a vertically reciprocable valve member having two ver-

tically spaced disks thereon connected by a central stem, the disks being associated with the respective ports to control the flow therethrough and closing in a downward direction, the body having a vertical bore therein above the upper port, a piston slideable in the bore and connected to the valve member, the valve member having a passage therein which extends through the stem, the upper end of the passage communicating with the space above the piston and its lower end communicating with the outlet chamber, and means to utilize the fluid flowing through the upper port to aspirate fluid from the lower end of the passage and thereby reduce the pressure above the piston, and a spring urging the valve member downwardly.

4. Automatic valve mechanism comprising a hollow body, a partition shaped as a horizontally positioned U dividing the interior of the body into an inlet chamber and an outlet chamber, the interior of the U forming a portion of the outlet chamber and each branch of the U having a port therein with the ports vertically aligned, a vertically reciprocable valve member having two vertically spaced disks thereon connected by a central stem, the disks being associated with the respective ports to control the flow therethrough and closing in a downward direction, the body having a vertical bore therein above the upper port, a piston slideable in the bore and connected to the valve member, the valve member having a passage therein which extends through the stem, the upper end of the passage communicating with the space above the piston and its lower end opening laterally into the outlet chamber, a baffle on the stem arranged to direct the fluid which flows downwardly along the stem from the upper port away from the lower end of the passage and thereby reduce the pressure above the piston, and a spring urging the valve member downwardly.

5. Automatic valve mechanism comprising a hollow body, a partition shaped as a horizontally positioned U dividing the interior of the body into an inlet chamber and an outlet chamber, the interior of the U forming a portion of the outlet chamber and each branch of the U having a port therein with the ports vertically aligned, a vertically reciprocable valve member having two vertically spaced disks thereon connected by a central stem, the disks being associated with the respective ports to control the flow therethrough and closing in a downward direction, the body having an opening therein above the upper port, a vertically movable fluid-pressure responsive device closing the said opening and connected to the valve member, the valve member having a passage therein which connects the outlet chamber with the space above the said device, means to utilize the fluid flowing through the upper port to aspirate fluid from the passage and thereby reduce the pressure above the said device, and a spring urging the valve member downwardly.

6. Automatic valve mechanism comprising a hollow body, a partition shaped as a horizontally positioned U dividing the interior of the body into an inlet chamber and an outlet chamber, the interior of the U forming a portion of the outlet chamber and each branch of the U having a port therein with the ports vertically aligned, a vertically reciprocable valve member having two vertically spaced disks thereon connected by a central stem, the disks being associated with the respective ports to control the flow therethrough and closing in a downward

direction, the body having an opening therein above the upper port, a vertically movable fluid-pressure responsive device closing the said opening and connected to the valve member, the valve member being shaped to provide a downwardly facing shoulder adjacent the stem and a passage connecting the space directly beneath the shoulder with the space above the said device, whereby fluid flowing downwardly from the upper port past the shoulder will aspirate fluid from the passage and reduce the pressure above the said device, and a spring urging the valve member downwardly.

7. Automatic valve mechanism comprising a hollow body, a partition shaped as a horizontally positioned U dividing the interior of the body into an inlet chamber and an outlet chamber, the interior of the U forming a portion of the outlet chamber and each branch of the U having a port therein with the ports vertically aligned, a vertically reciprocable valve member having two vertically spaced disks thereon connected by a central stem, the disks being associated with the respective ports to control the flow therethrough and closing in a downward direction, the body having an opening therein above the upper port, a vertically movable fluid-pressure responsive device closing the said opening and connected to the valve member, the valve member having a passage therein which extends through the stem, the upper end of the passage communicating with the space above the said device and its lower end communicating with the outlet

chamber, and means to utilize the fluid flowing through the upper port to aspirate fluid from the lower end of the passage and thereby reduce the pressure above the said device, and a spring urging the valve member downwardly.

8. Automatic valve mechanism comprising a hollow body, a partition shaped as a horizontally positioned U dividing the interior of the body into an inlet chamber and an outlet chamber, the interior of the U forming a portion of the outlet chamber and each branch of the U having a port therein with the ports vertically aligned, a vertically reciprocable valve member having two vertically spaced disks thereon connected by a central stem, the disks being associated with the respective ports to control the flow therethrough and closing in a downward direction, the body having an opening therein above the upper port, a vertically movable fluid-pressure responsive device closing the said opening and connected to the valve member, the valve member having a passage therein which extends through the stem, the upper end of the passage communicating with the space above the said device and its lower end opening laterally into the outlet chamber, a baffle on the stem arranged to direct the fluid which flows downwardly along the stem from the upper port away from the lower end of the passage and thereby reduce the pressure above the said device, and a spring urging the valve member downwardly.

CHARLES M. TERRY.
